UNITED STATES PATENT OFFICE.

JESSE B. LAINGOR AND GEORGE J. YERGER, OF KANSAS CITY, MISSOURI.

AIR-CRAFT.

1,021,105.

Specification of Letters Patent. Patented Mar. 26, 1912.

Application filed February 14, 1910. Serial No. 543,773.

To all whom it may concern:

Be it known that we, JESSE B. LAINGOR and GEORGE J. YERGER, citizens of the United States, residing at Kansas City, in the county of Jackson and State of Missouri, have invented certain new and useful Improvements in Air-Craft; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to air craft of the type which carries gas containers, and has for its principal objects to provide an air craft having novel, automatic and reliable safety devices for checking the descent of the craft in case the weight of the craft overcomes the buoyancy thereof, as in escape of the gas; to provide in lieu of one large gas bag, a large number of smaller gas bags; to provide means whereby the increasing tension upon the gas bags during the craft's ascent may be relieved by permitting a portion of the gas to pass into an empty bag or bags instead of wasting to atmosphere; to provide automatic means whereby in event of the rupture of any of the gas bags, the gas will be retained within all of the other gas bags; to provide a pair of motors, together with means by which either motor when disabled may be cut out and the other motor connected to the propeller driving mechanism without loss of time; and to provide the improved details of construction hereinafter described, and shown in the accompanying drawings, in which:

Figure 1 is a side elevation of an air craft constructed according to our invention, a portion of the wall of the engine room being broken out to expose the mechanism. Fig. II is an enlarged vertical section viewed on the line II—II of Fig. I, showing in full lines one of the parachute wings in extended position. Fig. III is an enlarged sectional plan, viewed on the line III—III of Fig. I. Fig. IV is a top plan view of the craft. Fig. V is a central vertical longitudinal section of the forward end of the craft. Fig. VI is a sectional detail view of one of the automatic gas retainer valves. Fig. VII is a

diagram showing in plan the arrangement 55 of the gas bags in the upper tier. Fig. VIII is a detail view. In Figs. II and V, the gas bags are shown in elevation.

Referring more in detail to the parts:— the frame of the craft is constructed to provide an upper gas containing section A, a lower gas containing section B, and a depending engine and pilot room C, which may be large enough to carry passengers. Between the upper and lower sections A, B, 60 and extending the full length of the craft, is an air passage D, of ample capacity to permit the air to pass from front to rear of the craft when the craft is in forward motion.

The top of the top frame section comprises 70 longitudinal members 1 and transverse members 2, and the sides of said section comprise vertical members 3 and longitudinal members 4. The lower frame section B, comprises the upper and lower longitudinal 75 members 1' and 4', the vertical members 3', and the transverse members 2'. Both the upper and lower sections are lined with wires 6, which are shown as parallel and spaced at the greatest practical distance apart; their 80 function being to restrain the sides of the gas bags 7.

The gas bags may be made of any suitable material, and are preferably, rectangular in form so as to fill completely their 85 respective portions of the holding frames, and are arranged side by side and in two rows, in each frame section A and B, as shown by Figs. II and VII. The two rows of gas bags in the lower frame section are 90 spaced, above the engine-room C, as shown in Fig. II, thus providing a large open space between said rows, through which the operators may have access to the propeller shaft bearings, the rudders, the upper gas 95 valves, and the upper gearings, all of which will be presently described. For supplying the bags with gas there are two (or more) tubes 8, (preferably flexible), each having valved connection 9 with the respective adjacent gas bags, and having at one end an open coupling 10 for connection with the gas reservoir (not shown). By the valves 9, gas may be admitted to and cut off from any bag independently of the others.

12 designates reserve bags which are not to be filled initially, but are left empty until the craft reaches an elevation at which

some gas must be released from the bags 7 to prevent bursting thereof. To this end, the rows of bags are interconnected as at 13 in Fig. VII, and the endmost bags 7 are connected by hose 14 with the reserve bags 12. In each tube 14 is a valve 15, which is preferably self closing and is operable by a cord 16, that extends into the engine room C. Each connection 13 is provided with a 10 double disk valve 17-17', Fig. VI, having a connecting stem 18, the valves being adapted to close upon either of two valve seats 19 but being normally retained in vertical position by the equal pressures in the bags with which the valve is connected. The stem 18 is held slidably within the guide webs, or cross-pieces 20, in or around which are apertures 21 for the passage of gas between the bags 7, which are connected 20 by the tube 13.

When it is desirable or necessary to relieve the gas bags 7, an operator pulls the cords 16 and opens the valves 15, whereupon gas will rush into the empty bags 12 and 25 will relieve all the bags 7 equally, owing to the connections 13 therebetween. Should any bags 7 be cut or torn when full, or burst by excessive pressure, the valves 17-18 in the tubes 13 connected with such 30 bag will be closed by the unbalanced pressures upon the valve disks 18, as one thereof will be practically exposed to atmosphere while the other will receive the pressure of the gas in the adjoining bag 7.

35 The great advantage of the multiplicity of gas bags over one or two very large bags, in contributing to the safety of the craft, will be obvious, without explanation. The storage of expanded gas is also a manifest 40 advantage, as heretofore, all gas permitted to escape from the container has been lost.

There are two propellers, 22, at the stern of the craft and in direct alinement with the aforesaid air passage D. The propeller 45 shafts 23 are shown as driven by bevel gears 24 from transverse shafts 25, which are driven by bevel gears 26 from a vertical shaft 27 which extends down into the engine room. 28 designates the bearings of said 50 shafts. At opposite sides of the shaft 27 are two duplicate motors or engines 29, each having a horizontal shaft 30. Each shaft 30 carries a clutch member 31. A shaft 32 in line with shafts 30 extends 55 through the pillar bearing 28', and has keyed thereon a bevel gear 33 that meshes with a gear 34 on the vertical shaft 27. The shaft 32 is provided with two clutch members 35, adapted to coact with the opposed 60 clutch members 31. By opening or closing said clutches 31-35, an operator may disconnect either motor from gear with shaft 27, or may disconnect both motors at the same time. Hence, should one motor break 65 down or stop running, the same can be in-

stantly thrown out of gear and the other thrown in gear, and this may be done without waiting for the propellers to come to a stop. They should, however, be slowed down before the second clutch is thrown in. 70 Friction gearing may be employed instead of spur gearing, if preferred, and the propellers 22 may be two bladed, and may be much larger than shown.

The rudders 36 for directing the craft to 75 right and left are located at the rear, and are hinged to the frame members 1, 4, 1' as at 37. They are connected by one or more rods 38, having pivotal connections at 39 and holding the rudders in parallel relation. Secured to each rudder is a laterally projecting arm 40, and connected to each arm 40 is a cord or wire 41; said cords or wires passing forwardly to a pulley hanger 42 provided with pulleys over which 85 said cords pass, downwardly, to a rotary drum 43, on which they are oppositely wound.

44 is a hand wheel on a shaft 45, which is geared by worm gearing 46 to the shaft 90 of drum 43. When the hand wheel 44 is turned, one cord or wire 41 will be drawn toward the drum 43 while the other cord or wire will be paid out, the incoming cord or wire actuating the rudder to which it is attached, and also the companion rudder through the medium of the connecting rod 38. Both of the members 41 are (practically) equally taut at all times.

The rudders 47 for directing the craft upwardly and downwardly, are located at the front, and are pivotally connected to the frame members 1', 4 at 48, so as to be movable vertically. The rudders are provided with arms 49, to which are attached cords 105 or wires 50, running rearwardly, over a pulley 51, and downwardly to a rotary drum 52, on which they are oppositely wound; said drum being adapted for rotation by a wheel 53 through the shaft 54 and worm 110 gear 55. The rudders 47 are connected at pivotal points 56, by a rod 57, which holds them in parallel relation. Their mode of operation is the same as described of the main rudders 36.

115 The engine and passenger room C is provided with side windows 60, the ends of the room being preferably left open, in order to reduce the air resistance. The corners of the room C are connected with the frame 120 members 4' fore and aft of said room, by tensioned wire braces, 63. In pursuance of the first named object of the invention, we provide at each side of the craft a wing 65, made of any suitable flexible material, which is strongly secured to the top frame member 1, and hangs against the upper frame, as shown in dotted lines, when the craft is ascending, or slowly descending. The lower edge of the wing is stiffened by a longitudi- 125 130

nal strip 65'. Secured to the lower frame members 1' and 4' are lugs or socket pieces 66, which are arranged to support vertical rods 67. Connected with the wing strip 65' are a series of depending stay-rods 68, whose lower ends are formed into eyes 69 which loosely embrace the vertical rods 67. When the wing 65 is fully distended the eyes 69 will bear against the upper socket pieces 10 66, and when the craft rises the wing and its stay-rods 68 will descend.

The above description applies to the wing apparatus at each side of the craft, and designated by like numerals. These wing 15 devices operate as automatic parachutes, whenever the car falls at a speed exceeding a certain rate, thereby preventing damage to the craft by striking any solid body at high speed downwardly. When the craft is 20 rising or moving forwardly, the wings 65 will offer no added resistance to the air.

It will be noted that the frame of the craft is somewhat pointed, as seen in side elevation, in order to lessen the craft's 25 resistance to the air. Preferably the lower part 77 of the stern frame is upwardly and rearwardly inclined.

Having thus described our invention,

what we claim as new therein and desire to secure by Letters-Patent is:—

In an air craft, a pair of frames, one superposed above the other and spaced therefrom to provide an air passage therebetween, gas bags contained within said frames, a cage suspended from the lower frame, the portion of said lower frame above said cage being open to provide for the passage of shafting and operating ropes therethrough, a horizontal rudder located at one end of the craft and extending on each side thereof, a vertical rudder located at the opposite end of the craft and extending above said upper frame, controlling ropes connected with said rudders and extending to said cage, propellers located at one end 45 of the craft, a motor carried in said cage and transmission mechanism connecting said propellers with said motors.

In testimony whereof we affix our signatures in presence of two witnesses.

JESSE B. LAINGOR.
GEORGE J. YERGER.
